UNITED STATES PATENT OFFICE.

FRANKLIN J. PERKINS, OF WOBURN, MASSACHUSETTS, ASSIGNOR TO
VAUGHN-ROOD MACHINE COMPANY, OF PORTLAND, MAINE.

FLESHING-MACHINE.

SPECIFICATION forming part of Letters Patent No. 769,017, dated August 30, 1904.

Application filed October 3, 1903. Serial No. 175,611. (No model.)

To all whom it may concern:

Be it known that I, FRANKLIN J. PERKINS, a citizen of the United States, residing in Woburn, in the county of Middlesex and State of Massachusetts, have invented an Improvement in Fleshing-Machines, of which the following description, in connection with the accompanying drawings, is a specification, like characters on the drawings representing like parts.

10 This invention relates to a machine for treating hides and skins, and is especially adapted for fleshing the same.

The invention has for its object to provide a simple and efficient machine of the class described with which a hide or skin can be fleshed in a continuous manner without the necessity of the operator reversing the skin, as now commonly practiced in the operation of fleshing. For this purpose I employ a plurality of work-supports and a plurality of operating-tools, toward and from which said work-supports are bodily movable, and a pinch or feed roll intermediate said work-supports and coöperating therewith to feed the hide or skin into and out of the machine, as will be described. These and other features of this invention will be pointed out in the claims at the end of this specification.

Figure 1 is a front elevation, with parts broken away, of a machine embodying this invention; Fig. 2, a side elevation of the machine shown in Fig. 1 looking toward the right, and Figs. 3 and 4 details in section to be referred to.

35 The machine herein shown as embodying this invention is provided with a plurality of operating-tools, herein shown as two in number and comprising bladed cylinders or rolls *a b*, journaled in boxes *e*, pivotally mounted in hangers *d*, secured to the side frames *e f* of the machine by the nuts *g*, which engage the threaded stems *h* of the hangers and secure said hangers in the position into which they are adjusted in a vertical plane.

40 45 The operating cylinders or rolls *a b* have coöperating with them a plurality of work-supports, which may be made as herein shown, and consist of two endless bands or aprons *j k*, which are movable toward and from the

operating cylinders or rolls. In the present 50 instance the band or apron *j* coöperates with the cylinder or roll *a*, and the band or apron *k* coöperates with the cylinder or roll *b*. The band or apron *j* is passed about rollers *m n*, the roller *m* being journaled in boxes *o*, pivotally supported by hangers or supports *p*, having threaded stems or rods *q*, which extend through the front portion of the side frames *e f* and are secured in their adjusted position by the nuts *r*, and the roll *n* is journaled in boxes 55 10, which are adjustably secured in side frames or supports *s*, pivotally mounted on a roll 13, which is journaled in suitable boxes supported, as herein shown, by a bracket or arm 14, attached to the side frame *e*, and by an upright 15, secured to the side frame *f* by the cross-bar 16. (See Fig. 1.) The endless band or apron *k* is passed about rolls 17 18, journaled in boxes 19 20, adjustably supported in the side frames *s*, the endless band *k* passing 60 under the roll 13, which may be made plane or fluted and which has the function of a feed-roll. The roll 13 is located between the endless bands *j k* and coöperates with both, as will be described.

75 The side frames or rocking supports *s* are adapted to be rocked about the feed-roll 13 as a center, so as to alternately move the endless bands *j k* toward and away from their coöperating cylinders *a b*, for a purpose as 80 will be described, and this result may be accomplished, as herein shown, by connecting the movable side frames *s* on the opposite sides of their center by means of links 21 22 with cranks or arms 23 24 on a rock-shaft 25, 85 supported by the framework of the machine. The rock-shaft 25 may be rotated in opposite directions from the front of the machine, as herein shown, by two foot-treadles 26 27, one of which, as 26, is secured to the rock-shaft 90 25, and the other of which, as 27, is secured to a second rock-shaft 28, supported by the framework of the machine and located, as herein shown, above the rock-shaft 25, to which it is coupled by the segmental gear 29, 95 fast on the shaft 28, meshing with the segmental gear 30, fast on the rock-shaft 25. In the present instance the depression of the

treadle 27 effects bodily movement of the work-supporting band *j* toward the knife-cylinder *a* and into substantially the position represented in Fig. 3, whereas the depression of the treadle 26 moves the work-supporting band *k* toward the knife-cylinder *b* and into substantially the position shown in Fig. 4.

The shaft 32 of the feed-roll 13 may and preferably will constitute the main or driving shaft of the machine, and in the present instance said shaft is shown as provided with two normally loose pulleys 33 34, which are rotated in opposite directions in any suitable manner, as by straight and cross belts, (not shown,) and said pulleys are adapted to be rendered fast on the shaft 32 by a clutch sleeve or member 35, which coöperates with clutch-hubs 36 37 on the said pulleys. The clutch-sleeve 35 is adapted to be moved in opposite directions by a cam-hub 38, fast on the rock-shaft 25 and provided with a cam-groove 39 in its periphery, into which extends the lower end of a lever 40, pivotally connected at its upper end with the clutch-hub 35. The bladed cylinders *a b* are rotated in opposite directions at a substantially high speed, and for this purpose they are provided with the belt-pulleys 41 42. The endless belt or apron *j* is driven from the main shaft 32 by a link chain 43, which is passed over a sprocket-wheel 44 on the shaft of the roll *m* and about a sprocket-wheel on the shaft 32 of the roll 13. The endless belt or apron *k* is driven from the main shaft 32, which for this purpose is provided with a gear 45, which meshes with gears or pinions (not shown) on the shafts of the rolls 17 18. The pulley 33 may be designated the "forward" pulley and the pulley 34 the "reverse" pulley.

40 The machine may be provided, as shown, with a delivery board or table 46, which is located below the endless belt *k* and inclined toward the rear of the machine.

The operation of the machine herein shown 45 may be briefly described as follows: The hide or skin to be treated is placed by the operator upon the endless bed or apron *j* when the latter is in its lowered position. The operator depresses the treadle 27, which rocks the shaft 25 a sufficient distance to cause the cam-groove 39 in the cam-hub 38 to throw the clutch-hub 35 into engagement with the hub 36 of the pulley 33, and thereby render said pulley fast on the driving-shaft 32, setting the latter in motion and effecting movement or travel of the endless beds or aprons *j k*, through the gearing above described, in the direction indicated by the arrows 50 in Fig. 3. The endless bed *j* carries the hide or skin with it and 50 between it and the feed-roll 13, which in turn coöperates with the endless bed *k* and carries what may be regarded as the inner end of the hide between said feed-roll and the bed *k*, thereby causing the hide to be wrapped about 55 the feed-roll, so as to obtain the desired grip

of the feed-roll on the hide or skin. When the hide or skin is gripped by the feed-roll 13, the operator further depresses the treadle 27 and rocks the shaft 25, so as to bring the hide or skin on the bed *j* into engagement with the knife-cylinder *a*, which fleshes or otherwise treats the portion of the hide subsequently presented to it by the bed *j*. When the hide or skin has been fed beyond the knife-cylinder *a* and sufficiently far so that its outer end passes out of engagement with the bed or apron *j* and falls upon the bed *k*, the operator releases the treadle 27 and depresses the treadle 26, which rocks the shaft 25 in the opposite direction and through the mechanism above described moves the bed *j* away from the cylinder *a* and moves the bed *k* toward the knife-cylinder *b* and into the position shown in Fig. 4, the clutch 35 being also moved to release the pulley 33 and engage the pulley 34, which rotates the feed-roll 13 in the reverse direction and causes the endless bed *k* to be moved in the direction opposite to that indicated by the arrow 50, thereby reversing the movement of the hide or skin, which is fed onto the inclined table 46 and is discharged out of the machine at its rear side. As the hide or skin is fed in the reverse direction it is subjected to the action of the knife-cylinder *b*, which fleshes or otherwise treats that portion which was not treated by the cylinder *a*. The cam-groove 39 is provided with a circular portion 55, (see Fig. 1,) which permits the rock-shaft 25 to be rocked still further after the clutch 35 has been engaged with the pulley 33.

From the above description it will be seen that the operator is relieved from considerable labor, as he is not required to handle the hide or skin after it is placed on the belt or endless bed *j*. Furthermore, the reversal of the direction of movement of the hide or skin is effected from the same side of the machine on which the operator starts the machine in operation.

I have herein shown the movable work-supports in the form of endless beds or aprons, and while I may prefer this construction I do not desire to limit my invention to the particular form of work-support shown.

The machine may and preferably will be provided with bonnets or guards 60 for the knife-cylinders, which bonnets may be pivotally secured to the side frames *e f*, as herein shown.

I claim--

1. In a machine of the class described, in combination, a plurality of knife-cylinders, a plurality of endless beds or aprons coöperating therewith, rocking supports for said endless beds, a feed-roll intermediate said endless beds and coöperating with the same, a rock-shaft connected with said rocking supports on opposite sides of the center thereof, a treadle to rock said rock-shaft in one direction, 125

a second treadle to rock said shaft in the opposite direction, and mechanism connecting said second treadle with said rock-shaft to enable the rock-shaft to be moved in opposite directions from the same side of the machine, substantially as described.

2. In a machine of the class described, in combination, a plurality of operating-tools, a plurality of work-supports coöperating therewith and movable bodily toward and from said tools, and means to simultaneously effect bodily movement of said work-supports in opposite directions with relation to said operating-tools, and means to effect travel of said work-supports in opposite directions, substantially as described.

3. In a machine of the class described, in combination, a plurality of operating-tools, a plurality of work-supports coöperating therewith and movable bodily toward and from said tools, and means to simultaneously effect bodily movement of said work-supports in opposite directions with relation to said operating-tools, means to effect travel of said work-supports in opposite directions, and a feed-roll coöperating with said work-supports and located intermediate thereof, substantially as described.

4. In a machine of the class described, in combination, a plurality of rotatable operating-tools, means to rotate said tools in opposite directions, traveling work-supports movable toward and from said operating-tools, means to move one of said traveling work-supports toward its coöperating operating-tool and to simultaneously move the other of said work-supports away from its coöperat-

ing operating-tool, and means to effect travel of said work-supports in opposite directions, substantially as described.

5. In a machine of the class described, in combination, a movable work-support, an operating-tool coöperating therewith to treat a portion of the hide or skin as the latter is moved in one direction into the machine, a second movable work-support to receive the hide or skin from the first-mentioned work-support, an operating-tool coöperating with said second work-support to treat the portion of the hide or skin which is unacted upon by the operating-tool coöperating with the first-mentioned work-support and as the hide or skin is moved in a reverse direction, and means to effect a reversal of movement of the hide or skin on its travel through said machine, substantially as described.

6. In a machine of the class described, in combination, a movable work-support to move the hide or skin into the machine, a second movable work-support to receive the hide or skin from the first-mentioned work-support, means to reverse the movement of said second work-support to effect a reversal of movement of the hide or skin while in the machine, and means to treat the hide or skin while on said work-supports, substantially as described.

In testimony whereof I have signed my name to this specification in the presence of two subscribing witnesses.

FRANKLIN J. PERKINS.
